DESIGN FOR A SCALE

Max Garbell, Chicago, Ill., assignor to Victor Adding Machine Company, Chicago, Ill., a corporation of Delaware

Application June 7, 1937, Serial No. 69,729

Term of patent 14 years

To all whom it may concern:

Be it known that I, Max Garbell, a citizen of the United States of America and a resident of Chicago, Cook County, Illinois, have invented a new, original, and ornamental Design for a Scale, of which the following is a specification, reference being had to the accompanying drawing forming a part thereof.

I claim:

The ornamental design for a scale substantially as shown.

MAX GARBELL.
